UNITED STATES PATENT OFFICE.

LEROY C. DOANE, OF MERIDEN, CONNECTICUT, ASSIGNEE TO THE MILLER COMPANY,
OF MERIDEN, CONNECTICUT, A CORPORATION OF CONNECTICUT.

SHADE SUPPORT.

Application filed March 31, 1925. Serial No. 19,575.

To all whom it may concern:

Be it known that I, LEROY C. DOANE, a citizen of the United States, and a resident of Meriden, in the county of New Haven and State of Connecticut, have invented certain new and useful Improvements in Shade Supports, of which the following is a specification.

The present invention relates to supports for shades and globes such as are used in electric lighting fixtures, and is more particularly directed toward the provision of a device for supporting a glass globe, reflector, shade, or the like, from a steel or other metallic support, such as a reflector.

An object of the present invention is to provide a shade or globe support which may be attached to the metal reflector in a simple, inexpensive, and expeditious manner without the use of screws, and wherein the machine work necessary is confined to small parts.

Another object of the invention is to provide a mechanism for supporting a shade from a metal reflector in which it is only necessary to punch two holes in the reflector so located that the shade supporting mechanism may be assembled with the metal reflector utilizing these holes to permit the movement of the shade supporting devices.

Another object of the invention is to provide a shade supporting device in which the mechanism for holding the shade may be locked in position to prevent removal of the shade, and in which the mechanism may be readily unlocked so that the weight of the shade will tend to dislocate the supporting parts in such a way that the shade may be removed.

Other and further objects of the invention will appear as the specification proceeds:

The accompanying drawings show, for purposes of illustration, one of the many possible forms in which the present invention may be embodied, it being understood that the drawings are illustrative of the invention rather than limiting the same.

In these drawings:

Fig. 1 is a top plan view of a reflector showing the shade mounting means;

Fig. 2 is a sectional view on the line 2—2 of Fig. 1, and showing a shade supported from the reflector;

Fig. 3 is a side elevation of one of the shade supporting members taken in the di-

rection of the arrow 3 of Fig. 2, a fragment of the reflector being shown; and

Fig. 4 is a similar elevational view of the other shade supporting arm being taken in the direction of the arrow 4 of Fig. 2.

While the shade supporting means may be attached to various devices, it is customary to support a shade underneath a reflector. Such a stamped metal reflector is shown at 10. It may be of any convenient form and size and is provided with the usual neck 10' to surround the socket and to facilitate attaching it to suitable supporting devices, not shown. The reflector 10 is provided with a cylindrical portion 11 adapted to receive the neck 12 of a glass shade, globe or the like. As here shown, the reflector is substantially flat as indicated at 13 between the neck 10' and the shade receiving portion 12. This flat area provides a shelf on which the shade supporting devices rest. This shelf is provided with two slots 14 and 15 arranged opposite one another and through which the shade supporting devices are passed.

A ring 16 which may be in the form of a casting is carried on this shelf. This ring is shown as having a lug 17 which is tapped as shown at 18 to receive two screws 19. These screws are utilized to fasten or attach an irregularly shaped shade supporting arm 20 made of a sheet metal stamping, and shown in detail in Fig. 4. This arm may be passed upwardly through the hole 14 in the reflector, and is provided with shoulders 21 engageable with the lower surface of the reflector to limit the upward movement of the arm. The upper end of the arm is bent over as indicated so as to overlie the lug 17. The lower end of this arm is bent outwardly as shown at 22 so as to engage with the shade 12 when the arm is in the position indicated in full lines. The opposite side of the ring 16 is here shown as being provided with an integral arm 23 which passes downwardly through the hole 15 in the metal reflector and which is spaced some distance inside the neck of the shade. A second irregularly shaped shade supporting member 24, also made of sheet metal, and shown more in detail in Fig. 3, is passed upwardly through the aperture 15 as indicated. The intermediate portion 25 of this shade supporting member is shaped so that it is adapted to lie adjacent the arm 23, while

105
100
110

the lower portion 26 is bent outwardly to engage the shade. The upper end 27 of this swinging member is narrower than the lower end so as to provide shoulders 28, similar to the shoulders 21 on the shade supporting member 20. As indicated in Fig. 2 the upper end 27 of this member is offset so as to provide a substantially horizontal portion 28' which rests on top of the metal reflector.

10 The upper end 27 is carried up above the upper surface of the ring 16 and is threaded to carry a thumb screw 29. This screw may be threaded through the hole in the supporting member and passed over above the upper 15 side of the ring 16.

In assembling the device the shade supporting members 20 and 24 are passed upwardly through the holes 14 and 15 respectively and the ring 16 is brought in position 20 so that the screws 19 may be inserted in place. The screw 29 is threaded in to the shade supporting member 25 and this completes the assembly of the device.

When one desires to insert a shade it is 25 merely necessary to grasp the lug 30 on the ring 16 and lift the left hand side of the ring to the position indicated in dot and dash lines. This will move the lower end 22 of the downwardly extending arm or 30 shade supporting member 20 as indicated, providing ample space for passing the neck of the shade up into position. During this movement the ring 16 and member 20 swing about the hole 14 as a pivot and the arm 23 35 moves upwardly through the hole 15. The upward movement of the arm 23 is limited by the inwardly extending lug 31 at the lower end of the arm which engages the metal of the reflector. When this ring is in 40 the upper position, the arm is moved out of the way of the swinging shade supporting member 24 so that it may swing or rock to bring the lower end of this arm away from the shade and permit it to pass upwardly. 45 The shade supporting member 24 cannot accidentally come out of place because the horizontal portion 28' rests on the top of the reflector.

After the shade has been inserted in place 50 the ring 16 is lowered to the full line position and the screw 29 is threaded over to bring its inner end above the ring. This locks the ring in place and prevents the swinging of the ring toward the position 55 which would release the reflector. There is a tendency toward such swinging movement on account of the weight of the reflector imposed above the lower end of the shade supporting member 20. By locking the ring with the shade supporting member 24, such movement of the ring is prevented, for the shoulders 28 on the strap 24 engage under the reflector and prevent upward movement of these parts. The lower end of the 60 arm 23 may be recessed as indicated at 65

to cooperate with a curved portion 33 on the arm 24 so as to more positively position the lower end of the shade supporting member 24 when holding the shade and so as to permit additional freedom of movement of the parts when the arm has been raised to permit removal of the shade. This is on account of the bringing of the recess 32 up 70 near the pivot point of the shade supporting member 24, which will permit this member to swing freely through a wide range of movement.

When one desires to remove the shade it is merely necessary to support the shade with one hand and unthread the screw 29 with the other. As soon as the screw is sufficiently unthreaded one may lower the shade and its weight will bear down on the lower end of the arm 20 thereby swinging the ring upwardly and drawing the arm 23 from behind the shade supporting strap 24 permitting the strap to swing inwardly so that the shade may be withdrawn. When the parts are in this position the screw may, if desired, be threaded inwardly against the side of the arm 23 to hold the parts in place until the reflector is again inserted.

It is obvious that the invention may be embodied in many forms and constructions and I wish it to be understood that the particular form shown and described is but one of the many forms. Various modifications and changes being possible, I do not wish in any way to limit myself with respect thereto.

I claim:

1. In a shade support, a reflector, having a portion adapted to receive the neck of a shade, a depending arm passing through an aperture in the reflector and movable vertically, the arm being spaced from the inside of the shade, a shade supporting member supported from the reflector in a position to be forced outwardly by the arm to engage the shade when the arm is in its lower position, and being releasable from said shade when the arm is raised, and means to lock the arm in the lower position.

2. In a shade support, a reflector, having a portion adapted to receive the neck of a shade, a depending arm passing through an aperture in the reflector and movable vertically, the arm being spaced from the inside of the shade, a shade supporting member passing through the aperture and being supported from the reflector alongside the arm in a position to be forced outwardly by the arm to engage the shade when the arm is in its lower position, and being releasable from said shade when the arm is raised, and means to lock the arm in the lower position.

3. In a shade support, a reflector, having a portion adapted to receive the neck of a shade, a depending arm passing through an

aperture in the reflector and movable vertically, the arm being spaced from the inside of the shade, a shade supporting member supported from the reflector in a position to be forced outwardly by the arm to engage the shade when the arm is in its lower position, and being releasable from said shade when the arm is raised, and a member carried by the supporting member 10 for locking the arm in the lower position.

4. In a shade support, a reflector, having a portion adapted to receive the neck of a shade, a depending arm passing through an aperture in the reflector and movable vertically, the arm being spaced from the inside of the shade, a shade supporting member swingingly supported from the reflector in a position to be forced outwardly by the arm to engage the shade when the arm is in its lower position, and being releasable from said shade when the arm is raised, means to interlock the arm and swinging supporting member with one another when the arm is in the lower position, and means to lock one 25 of said interlocked parts with the reflector to prevent release of the shade.

5. In a shade support, a reflector, having a portion adapted to receive the neck of a shade, a depending arm passing through an aperture in the reflector and movable vertically, the arm being spaced from the inside of the shade, a shade supporting member supported from the reflector in a position to be forced outwardly by the arm to engage the shade when the arm is in its lower position, and being releasable from said shade when the arm is raised, a ring attached to the arm and supported by the reflector, a second shade supporting member attached 35 to the ring and disposed to engage the shade when the arm is lowered, the raising of the arm moving the ring and swinging the second shade supporting member to disengage it from the shade, and means to lock the arm and ring in the lower position.

6. In a shade support, a reflector, having a portion adapted to receive the neck of a shade, a depending arm passing through an aperture in the reflector and movable vertically, the arm being spaced from the inside of the shade, a shade supporting member swingingly supported from the reflector in a position to be forced outwardly by the arm to engage the shade when the arm is in its lower position, and being releasable from said shade when the arm is raised, a ring attached to the arm and supported by the reflector, a second shade supporting member attached to the ring and disposed to engage the shade when the arm is lowered, the raising of the arm moving the ring and swinging the second shade supporting member to disengage it from the shade, means to interlock the arm and swinging supporting member with one another when the arm 65

is in the lower position, and means to lock one of said interlocked parts with the reflector to prevent release of the shade.

7. A shade support comprising, a metal reflector having a portion adapted to support a ring, a ring resting thereon, said ring having two arms which pass through apertures in the reflector, the lower end of one of the arms having a shade supporting portion, said arm and the corresponding aperture providing a pivot about which the ring may be swung, a second shade supporting member carried by the reflector adjacent the other arm on the ring in a position to be swung into position to engage a shade when said arm is lowered, and means to lock the ring in the lower position. 70

8. A shade support comprising, a metal reflector having a portion adapted to support a ring, a ring resting thereon, said ring having two arms which pass through apertures in the reflector, the lower end of one of the arms having a shade supporting portion, said arm and the corresponding aperture providing a pivot about which the ring may be swung, a second shade supporting member carried by the reflector adjacent the other arm on the ring in a position to be swung into position to engage a shade when said arm is lowered, and a member carried by the second shade supporting member and engageable with the ring to hold the ring in the lower position. 80

9. A shade support comprising, a metal reflector having a portion adapted to support a ring, a ring resting thereon, said ring having two arms which pass through apertures in the reflector, the lower end of one of the arms having a shade supporting portion, said arm and the corresponding aperture providing a pivot about which the ring may be swung, a second shade supporting member carried by the reflector adjacent the other arm on the ring in a position to be swung into position to engage a shade when said arm is lowered, and a screw threaded through the second shade supporting member and passing above the ring to hold the ring in the lower position. 90

10. In combination, a reflector, a shade, and means to support the shade from the reflector, said means comprising, a ring swingingly carried by the reflector, a depending arm carried by the ring and engageable inside the shade when in one position and disengaged from the shade when in the other position, and means to lock the ring in the former position. 115

11. In combination, a reflector, a shade, and means to support the shade from the reflector, said means comprising, a ring swingingly carried by the reflector, a depending arm carried by the ring and engageable inside the shade when in one position and disengaged from the shade when 125

in the other position, a swinging globe supporting member carried by the reflector, and means interconnecting the member with the ring to lock the ring in the former position.

12. In combination, a reflector, a shade, and means to support the shade comprising a swingingly supported ring having a depending arm engageable under the neck 10 of the shade, the weight of the shade tending to swing the opposite side of the shade upwardly, a second shade engaging member swingingly carried by the reflector, and means interconnecting said second shade engaging member and said opposite side of the ring to hold the shade engaging member against the shade when said opposite side is in its lower position.

13. In combination, a reflector, a shade, 20 and means to support the shade comprising a swingingly supported ring having depending arms engageable under the neck of the shade, the weight of the shade tending to swing the opposite side of the shade upwardly, a second shade engaging member swingingly carried by the reflector, means interconnecting said second shade engaging member and said opposite side of the ring to hold the shade engaging member 25 against the shade when said opposite side is in its lower position, and means for interlocking said ring and member to prevent the release of the shade.

14. A shade support, comprising, a supporting member, a ring carried on said supporting member, apertures in the supporting member adjacent the opposite side of the ring, shade engaging members passed upwardly through the apertures and having shoulders to limit their upward movement, one of said shade engaging members being attached to the ring, the second shade engaging members being swingingly carried by the supporting member, and means carried by the ring for forcing said second shade engaging member outwardly to engage the shade when the ring is lowered to the position to move the attached shade engaging member outwardly.

15. A shade support, comprising, a supporting member, a ring carried on said supporting member, apertures in the supporting member adjacent the opposite side of the ring, shade engaging members passed upwardly through the apertures and hav-

ing shoulders to limit their upward movement, one of said shade engaging members being attached to the ring, the second shade engaging members being swingingly carried by the supporting member, means carried by the ring for forcing said second shade engaging member outwardly to engage the shade when the ring is lowered to the position to move the attached shade engaging member outwardly, and a device 60 engageable with the ring to lock it in said last mentioned position.

16. A shade support, comprising, a supporting member, a ring carried on said supporting member, apertures in the supporting member adjacent the opposite side of the ring, shade engaging members passed upwardly through the apertures and having shoulders to limit their upward movement, one of said shade engaging members being 70 attached to the ring, the second shade engaging members being swingingly carried by the supporting member, means carried by the ring for forcing said shade engaging member outwardly to engage the shade 75 when the ring is lowered to the position to move the attached shade engaging member outwardly, and a member movably mounted on the second shade engaging member for engaging the ring to prevent release of 80 the shade.

17. In a shade support, a normally horizontal ring having an arm depending from one side of the ring and arc shaped about a center at the opposite side of the ring. 90

18. In a shade support, a normally horizontal ring having an arm depending from one side of the ring and arc shaped about a center at the opposite side of the ring, and a shade engaging member attached to 95 said opposite side of the ring and extending downwardly and outwardly.

19. A shade supporting member having a normally vertical intermediate portion, a substantially horizontal lower portion for 100 engaging the shade, a substantially horizontal portion above the intermediate portion, a shoulder at the upper end of the intermediate portion, and an upwardly extending portion at the end of the second 105 horizontal portion.

Signed at Meriden, in the county of New Haven and State of Connecticut, this 27 day of March 1925.

LEROY C. DOANE.
